(57) **CLAIM**

The ornamental design for a battery box fairing, as shown and described.

DESCRIPTION

FIG. 1 is an isometric view of a truck fairing showing a battery box fairing of our new design;

FIG. 2 is an oblique view of a battery box fairing showing our new design;

FIG. 3 is a side view;

FIG. 4 is a top view; and

FIG. 5 is a rear view; and,

FIG. 6 is a bottom view.

The broken line showing of the truck of FIG. 1 depicts environment and is not part of the claimed design.

FIGS. 1–6 illustrate a first embodiment of our novel design suitable for use on the left side of a vehicle. Our novel design also includes a second embodiment suitable for use on the right side of a vehicle, which is mirror symmetrical to FIGS. 1–6 and therefore not separately illustrated.
